(57) **CLAIM**

I claim the ornamental design for an elongate light fixture, as shown and described.

DESCRIPTION

FIG. 1 is a front view of a first embodiment of my design for an elongate light fixture;

FIG. 2 is a right side view of the elongate light fixture embodiment shown in FIG. 1;

FIG. 3 is a left side view of the elongate light fixture embodiment shown in FIG. 1;

FIG. 4 is a top plan view of the elongate light fixture embodiment shown in FIG. 1;

FIG. 5 is a bottom view of the elongate light fixture embodiment shown in FIG. 1;

FIG. 6 is a rear view of the elongate light fixture embodiment shown in FIG. 1;

FIG. 7 is a front view of a second embodiment of my design for an elongate light fixture;

FIG. 8 is a right side view of the elongate light fixture embodiment shown in FIG. 7;

FIG. 9 is a left side view of the elongate light fixture embodiment shown in FIG. 7;

FIG. 10 is a top plan view of the elongate light fixture embodiment shown in FIG. 7;

FIG. 11 is a bottom view of the elongate light fixture embodiment shown in FIG. 7;

FIG. 12 is a rear view of the elongate light fixture embodiment shown in FIG. 7;

FIG. 13 is a front view of a third embodiment of my design for an elongate light fixture;

FIG. 14 is a right side view of the elongate light fixture embodiment shown in FIG. 13;

FIG. 15 is a left side view of the elongate light fixture embodiment shown in FIG. 13;

FIG. 16 is a top plan view of the elongate light fixture embodiment shown in FIG. 13;

FIG. 17 is a bottom view of the elongate light fixture embodiment shown in FIG. 13; and,

FIG. 18 is a rear view of the elongate light fixture embodiment shown in FIG. 13.

The broken lines shown in the drawing disclosure illustrate environmental structure and form no part of the claimed design.
